DESIGN FOR A TOILET SEAT HINGE

Vernon W. Campbell, Nashua, N. H., assignor to
C. F. Church Mfg. Co., Holyoke, Mass., a corpo-
ration of Massachusetts

Application August 10, 1934, Serial No. 52,893

Term of patent 7 years

To all whom it may concern:

Be it known that I, VERNON W. CAMPBELL, a citizen of the United States, residing at Nashua, in the county of Hillsboro and State of New Hampshire, have invented a new, original, and ornamental Design for a Toilet Seat Hinge, of which the following is a specification, reference being had to the accompanying drawing, forming part thereof.

Fig. 1 is a front elevation of a toilet seat hinge

in a raised position showing my new design;
Fig. 2 is a top plan view of the same with the hinge in a lowered position; and

Fig. 3 is a side elevation of the same, the parts being shown in lowered position.

I claim:

The ornamental design for a toilet seat hinge substantially as shown and described.

VERNON W. CAMPBELL.
